MULTISTAGE COMPRESSOR

Harry Ralph Ricardo, London, England

Application September 16, 1942, Serial No. 458,547
In Great Britain September 29, 1941

6 Claims. (Cl. 230—184)

This invention relates to multi-stage compressors of the reciprocating type and has for its object to provide a compact and simple construction adapted more especially for the compression of air or gas.

According to this invention in the first stage of the compressor a higher rotational speed is employed than in the subsequent stages, the first stage being operated by a crankshaft which is rotated at a speed greater than that of the crankshaft by which are operated the pistons of the subsequent stages. There is at least one cylinder with piston therein constituting the first stage this piston being reciprocated by a crankshaft driven at relatively high speed and pistons in cylinders constituting the subsequent stages which are reciprocated by a second crankshaft driven at a lower speed and conveniently through gearing from the first crankshaft. The valves of each cylinder in the first stage are positively actuated mechanically, while the valves of the cylinders in each subsequent stage operate automatically. These inlet and delivery valves of the first stage are of the piston type and are operated by a shaft rotating at half the speed of the crankshaft of the first stage, and the opening and closing of the inlet and delivery ports is effected while these piston valves are moving at their maximum velocity, that is during the middle portion of the stroke of each valve. The shaft which operates these piston valves is conveniently in the crankshaft which reciprocates the pistons in the cylinders of the subsequent stages these cylinders and pistons being disposed coaxially with the piston valves to which those higher stage pistons are connected so that they are actuated through the valves. Each of the latter thus acts as a cross-head to which is connected on the one hand the piston of a higher stage and on the other hand a connecting rod running from a crank on the second crankshaft. In a convenient arrangement the delivery valve of the first stage is connected to and serves as a cross-head for the piston of the third stage, this valve actuated from a crank on a crankshaft driven through gearing at half speed from the crankshaft which operates the first stage. To a second crank on this half speed crankshaft is connected the inlet or suction valve of the first stage cylinder and this valve in turn acts as a cross-head for and is connected to the piston of the second stage cylinder. From this piston may extend a plunger which reciprocates in the cylinder of a fourth stage. This latter may be omitted if the compressor is constructed with only three stages.

Suitable intercoolers may be provided between the various stages, and an aftercooler may be provided to cool the gas delivered by the last or highest stage.

5 The accompanying drawings illustrate diagrammatically and by way of example a construction of four-stage compressor according to this invention. In these drawings,

10 Figure 1 is a vertical sectional elevation of the compressor the section being taken as on the line 1—1 in Figure 2 looking in the direction of the arrows. The section shows the piston valves for the first stage and the cylinders of the second, third and fourth stages, the section being taken in the plane in which lies the axis of the crankshaft by which are reciprocated these valves and the pistons in these cylinders.

15 Figure 2 is a plan of the compressor shown in Figure 1.

20 Figure 3 is a transverse vertical section on the line 3—3 in Figure 1, and the broken line 3—3 in Figure 2, the section showing the piston and cylinder of the first stage, the inlet valve therefore, and the cylinders, pistons and valves of the second and fourth stages.

25 Figure 4 is a vertical section similar to Figure 3, but taken on the line 4—4 in Figure 1 and on the broken line 4—4 in Figure 2, and showing the piston and cylinder of the first stage, the delivery valve for that cylinder, and the cylinder and piston of the third stage.

30 There are two crankshafts of which the one A may be referred to as the main crankshaft while the other B may be referred to as the second crankshaft or layshaft. The compressor is driven by power applied in some convenient manner and from a suitable source to the main shaft A, and the layshaft B is driven by gearing C from the shaft A so that the layshaft B will be rotated at half the speed of the main shaft A. These two shafts A and B are parallel and at no great distance apart with the axis of the shaft B lying in a horizontal plane above the similar plane in which lies the axis of the shaft A, as can be seen in Figures 3 and 4. The vertical plane in which lies the axis of the shaft B and the axes of the pistons driven from that shaft is set back behind the vertical plane in which lies the axis of the cylinder of the first stage as can be seen in Figure 2 as well as in Figures 3 and 4. Considered in plan, as seen in Figure 2, the cylinder D of the first stage with the piston E therein appears as having at one side of it the cylinders F and G with the piston valves H and J therein. Coaxial with the cylinder F and above it are the cylinder

K of the second stage with the piston L reciprocating therein, and the cylinder M of the fourth stage with the plunger piston N therein. Co-axial with the cylinder G and above it is the cylinder O of the third stage with the piston P which is reciprocated in it.

The piston valves of the first stage are hollow and the suction valve H controls an inlet port D¹ to the first stage cylinder D and an inlet port F¹ from the atmosphere to the valve cylinder F as seen in Figure 3. The valve J controls the delivery port D² from the cylinder D and the compressed air passes through the valve J and cylinder G into the passage G¹ which communicates conveniently with an intercooler of suitable type which is not shown in the drawing. From this first stage intercooler the air passes the suction valve K¹ into the second stage cylinder K whence it is delivered past the delivery valve K² to a second intercooler, also not shown in the drawing. From this second stage intercooler the air goes past the suction valve O¹ into the third stage cylinder O and thence past the delivery valve O² to a third stage intercooler which is not shown. Finally the air enters the fourth stage cylinder M past the valve M¹ and is delivered past the valve M².

The hollow piston valves H and J are substantially similar in their general structure with ports formed in the walls of their upper parts. In the valve H which functions also as a cross-head, is a partition H¹ below which is carried the gudgeon pin H² through which the valve is connected to the crankshaft B. From this partition H¹ a coupling rod Q extends to the piston L of the second stage. This coupling rod has curved faces at its ends which engage correspondingly curved bearing blocks carried respectively by the partition H¹ and the piston L. By suitable means the ends of the coupling rod are maintained in engagement with the curved seats in these blocks. The arrangement obviates difficulty which might arise owing to some lack of alignment between the cylinders F and K. There is a similar coupling rod between a partition J¹ in the piston valve J, which also functions as a cross-head for the gudgeon pin J², and the piston P of the third stage.

By leading the air from the first stage cylinder D into the end of the cylinder G beneath the piston P in the cylinder O of a higher stage the pressure difference is reduced on the rings of the piston of the higher stage.

There may be a throttle valve of suitable form in the induction passage leading to the suction valve inlet port F¹. In the head of the cylinder D of the first stage there may be a port controlled by a poppet valve which has to be lifted against spring action. This valve may be lifted by a hand lever operative on the end of the valve spindle when it is desired to relieve the pressure in the cylinder or prevent compression as at starting or for unloading.

The valves of the second, third and fourth stage cylinders are of some type which will operate automatically. In the case of the second stage cylinder K each of the valves K¹ and K² is a disc which is mounted freely, except for a light spring, between a perforated seat member and a retaining member. The ports controlled by these valves are in the head of the cylinder K. With regard to the third stage the piston P is of trunk form with the trunk of substantial length. The end of the cylinder O and the face of the piston

are conical the ports being in the sloping end of the cylinder. The inlet valve O¹ is preferably of the poppet type and the delivery valve O² is a disc actuated on by a spring.

5 What I claim as my invention and desire to secure by Letters Patent is:

1. In a multi-stage compressor of the reciprocating type the combination of at least one cylinder with piston therein constituting the first stage of the compressor, at least one other cylinder with piston therein constituting a subsequent stage, a crankshaft to which is connected the piston in the said cylinder of the first stage, a second crankshaft to which is connected the

10 piston in the said cylinder of a subsequent stage, valves associated with the said cylinder of the first stage with means whereby these valves are positively actuated mechanically, valves associated with the said cylinder of a subsequent 15 stage with means by which these valves are actuated automatically, and means whereby the said second crankshaft is rotated at a speed which is less than the speed at which the said first crankshaft is driven.

2. In a multi-stage compressor of the reciprocating type the combination of at least one cylinder with piston therein constituting the first stage of the compressor, at least one other cylinder with piston therein constituting a subsequent

20 stage, a crankshaft to which is connected the piston in the said cylinder of the first stage, a second crankshaft to which is connected the piston in the said cylinder of a subsequent stage, valves associated with the said cylinder of the

25 first stage, means by which these valves are actuated from the said second crankshaft, valves associated with the said cylinder of a subsequent stage with means by which these valves are actuated automatically, and means whereby the said second crankshaft is rotated at a speed which is less than the speed at which the said first crankshaft is driven.

3. A multi-stage compressor of the reciprocating type comprising the features as set out in claim 2 in which piston valves connected to and reciprocated by the said second crankshaft function as the inlet and delivery valves of the said cylinder of the first stage.

4. In a multi-stage compressor of the reciprocating type the combination of at least one cylinder with piston therein constituting the first stage of the compressor, at least two cylinders each with a piston therein and constituting sub-

30 sequent stages of the compressor, a crankshaft to which is connected the piston in the said cylinder of the first stage, a second crankshaft to which are connected the pistons in the cylinders of the subsequent stages, piston valves connected to and reciprocated by the second crankshaft

35 valves functioning as the inlet and delivery valves of the said cylinder of the first stage and being respectively coaxial with the cylinders of the higher stages, valves associated with the said cylinders of stages subsequent to the first stage with means by which these valves are actuated automatically, and means whereby the said second crankshaft is rotated at a speed which is less than the speed at which the said first crankshaft is driven.

5. In a multi-stage compressor of the reciprocating type the combination of at least one cylinder with piston therein constituting the first stage of the compressor, at least two cylinders each with a piston therein and constituting sub-

40 sequent stages of the compressor, a crankshaft to which is connected the piston in the said cylinder of the first stage, a second crankshaft to which are connected the pistons in the cylinders of the subsequent stages, piston valves connected to and reciprocated by the second crankshaft

45 valves functioning as the inlet and delivery valves of the said cylinder of the first stage and being respectively coaxial with the cylinders of the higher stages, valves associated with the said cylinders of stages subsequent to the first stage with means by which these valves are actuated automatically, and means whereby the said second crankshaft is rotated at a speed which is less than the speed at which the said first crankshaft is driven.

6. In a multi-stage compressor of the reciprocating type the combination of at least one cylinder with piston therein constituting the first stage of the compressor, at least two cylinders each with a piston therein and constituting sub-

50 sequent stages of the compressor, a crankshaft to which is connected the piston in the said cylinder of the first stage, a second crankshaft to which are connected the pistons in the cylinders of the subsequent stages, piston valves connected to and reciprocated by the second crankshaft

55 valves functioning as the inlet and delivery valves of the said cylinder of the first stage and being respectively coaxial with the cylinders of the higher stages, valves associated with the said cylinders of stages subsequent to the first stage with means by which these valves are actuated automatically, and means whereby the said second crankshaft is rotated at a speed which is less than the speed at which the said first crankshaft is driven.

7. In a multi-stage compressor of the reciprocating type the combination of at least one cylinder with piston therein constituting the first stage of the compressor, at least two cylinders each with a piston therein and constituting sub-

sequent stages of the compressor, a crankshaft to which is connected the piston in the said cylinder of the first stage, a second crankshaft to which are connected the pistons in the cylinders of the subsequent stages, piston valves connected to and reciprocated by the second crankshaft these valves functioning as the inlet and delivery valves of the said cylinder of the first stage and being respectively coaxial with and acting as crossheads for the pistons in the cylinders of the higher stages, valves associated with the said cylinders of stages subsequent to the first stage with means by which these valves are actuated automatically, and means whereby the said second crankshaft is rotated at a speed which is less than the speed at which the said first crankshaft is driven.

6. In a multi-stage compressor of the reciprocating type, the combination with at least one cylinder with piston therein constituting the first stage of the compressor, at least two cylinders each with piston therein and constituting sub-

sequent stages of the compressor, at least two of these cylinders of subsequent stages being coaxial with the pistons therein connected, a crankshaft to which is connected the piston in the said cylinder of the first stage, a second crankshaft to which are connected the pistons in the cylinders of the subsequent stages, piston valves connected to and reciprocated by the second crankshaft these valves functioning as the inlet and delivery valves of the said cylinder of the first stage and being respectively coaxial with and acting as crossheads for the pistons in the cylinders of the higher stages, valves associated with the said cylinders of stages subsequent to the first stage with means whereby these valves are actuated automatically, and means whereby the said second crankshaft is rotated at a speed which is less than the speed at which the said first crankshaft is driven.
